(57) **CLAIM**

The ornamental design for a “moisture sensing apparatus,” as shown.

DESCRIPTION

FIG. 1 is a front view of a “moisture sensing apparatus” showing my new design;

FIG. 2 is a rear view thereof;

FIG. 3 is a right side view thereof;

FIG. 4 is a left side view thereof;

FIG. 5 is a top plan view thereof; and,

FIG. 6 is a bottom plan view thereof.
